Primary Examiner — Stella Reid*Assistant Examiner* — Keli L Hill(74) *Attorney, Agent, or Firm* — Amy I Ahn-Roll; Leonard W. Lewis(57) **CLAIM**

The ornamental design for a bottle, as shown and described.

DESCRIPTION

FIG. 1 is a perspective view of one embodiment of a bottle, showing our new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8 is a cross-sectional view thereof, taken along line 8—8;

FIG. 9 is a perspective view of a second embodiment of a bottle, showing our new design;

FIG. 10 is a front elevational view thereof;

FIG. 11 is a rear elevational view thereof;

FIG. 12 is a side elevational view thereof;

FIG. 13 is an opposite side elevational view thereof.

FIG. 14 is a top view thereof; and,

FIG. 15 is a bottom view thereof.

The broken lines shown in the center of FIGS. 9-15 represent the boundaries of the claimed design and indicate that a specific length and width forms no part of the claimed design. All other broken lines are included for the purpose of illustrating the unclaimed portions of the article and form no part of the claim.
